UNITED STATES PATENT OFFICE.

JOHN J. HOPPES, OF SPRINGFIELD, OHIO.

FEED-WATER PURIFIER.

SPECIFICATION forming part of Letters Patent No. 445,407, dated January 27, 1891.

Original application filed June 30, 1888, Serial No. 278,692. Divided and this application filed October 10, 1890. Serial No. 367,704. (No model.)

To all whom it may concern:

Be it known that I, JOHN J. HOPPES, a citizen of the United States, residing at Springfield, in the county of Clark and State of Ohio, have invented certain new and useful 5 Improvements in Feed-Water Purifiers, of which the following is a specification.

My invention relates to improvements in feed-water purifiers for steam-boilers; and it 10 particularly relates to that class of purifiers which are connected directly to the steam-boiler in the manner set forth in my pending application, Serial No. 278,692, filed June 30, 1888, this application being filed as a division 15 of the above-named application.

The object of my invention is to provide means for carrying off air or gases that collect in the top of purifiers of this character and at the same time provide means for operating the boiler feeder or pump. This I accomplish by connecting to the purifier a pipe leading to the boiler-feeder or other device requiring a steam-supply, and thus creating a circulation through the purifier by 25 which any air or gases therein contained will be drawn off.

In the accompanying drawings, which form a part of this specification, Figure 1 is a perspective view of a feed-water-purifier mechanism embodying my invention. Fig. 2 is a 30 longitudinal sectional view, also in perspective, of a purifier, showing the arrangement of the connections thereto.

Like parts are indicated by similar letters 35 of reference throughout the several views.

In the said drawings, A represents a steam-boiler of ordinary construction. B is a steam-drum attached thereto.

C is a purifier, which may be of any well-known construction adapted to be connected 40 directly to the boiler and supplied with steam therefrom.

e is the blow-off or discharge pipe leading 45 from the purifier and provided with the usual stop-valves for discharging the heater for cleaning or other purposes.

The purifier C is preferably connected directly to the steam-drum B by a pipe a. The feed-water enters through a pipe b and passing 50 over a series of pans or shelves, as the

case may be, of the purifier is discharged into the boiler below the water-line thereof through a pipe-connection c. Since the pressure in the purifier C is substantially the same as that in the boiler A, means must be provided for forcing the feed-water through the supply-pipe b into said purifier. This is preferably accomplished by an ordinary steam-pump boiler-feeder D in the ordinary manner.

In purifiers of this character connected directly to the steam-boiler there is a flow of steam from the boiler to the purifier caused by the condensation of the steam therein owing to the supply of feed-water to said purifier.

The feed-water for steam-boilers contains in many cases large quantities of foreign matter, which when heated gives off carbonic-acid gas, hydrochloric-acid gas, muriatic fumes, or other gases. Inasmuch as there is 70 a flow of steam from the boiler to the purifier these gases collect in the purifier, and if not removed fill the purifier to such an extent as to materially interfere with the purifying effect of the steam therein. To over- 75 come this difficulty I provide an additional connection to the purifier C, which leads direct to the boiler-feeder or other steam-using device, which thus continually drives or carries off the gases, air, or steam from the said 80 purifier, creating a circulation therein, which keeps the same at all times full of live steam adapted to act upon the feed-water therein.

In Fig. 1 the preferable method of forming this connection is shown. It consists in connecting the supply-pipe d, which furnishes steam to the pump or boiler-feeder D, to the purifier C through a branch pipe d', supplied with a T-connection d², which is also connected by a pipe d³ to the boiler-supply, the pipes d³ and d', respectively, being provided with stop-valves d⁵ and d', by which the steam-supply for the feed-pump may be drawn either from the boiler or from the purifier, as desired, or partly from both. By this arrangement if the purifier in any event is cut off for any reason the boiler-feeder may receive the steam-supply direct from the boiler. It is evident that the same result may be accomplished by running the pipe d from the 100

purifier to any other steam-using device beside the boiler-feeder D which requires a steam-supply and will cause a circulation through the purifier, which will carry off the 5 gases therein contained and keep the same supplied with live steam direct from the boiler through the main boiler-connection a. I preferably make the circulating connection with the boiler-feeder, since the supply of feed- 10 water for the purifier is dependent upon the said boiler-feeder, and as the gases collected in the purifier come from the water supplied by said boiler-feeder, the action of the pump which supplies the water containing the said 15 gases will also furnish the means for removing said gases.

It should be also stated that when a boiler-feeder is used for supplying the boilers and the circulating connection is made thereto 20 from the purifier the usual direct connection from said boiler-feeder to the boilers is employed, as indicated in dotted lines in the drawings, the discharge-pipe from said boiler-feeder being provided with suitable valves, so 25 that said pump may be caused to discharge into the purifier or into the boilers direct in a well-known manner.

Having thus described my invention, I claim—

1. The combination, with a feed-water purifier connected directly to a steam-boiler, of a separate steam-connection leading from said purifier to a steam-using device, said steam-connection being provided with a branch to the boiler, and stop-valves in the 30 35 respective branches of said steam-connection, substantially as specified.

2. The combination, with a feed-water purifier connected directly to a steam-boiler, of a boiler-feeder adapted to supply said purifier, and a steam-connection from said boiler-feeder to said purifier, said steam-connection being provided with a branch to the steam-boiler and stop-valves in the respective 40 45 branches of the said steam-connection, whereby the steam-supply from the boiler or purifier may be cut off, as desired, substantially as specified.

In testimony whereof I have hereunto set my hand this 8th day of October, A. D. 1890.

JOHN J. HOPPES.
